W. A. WILLIAMS

ELEVATOR DOOR LATCH

Filed Sept. 26, 1923

Inventor

WILLIAM A. WILLIAMS

by *Frank J. Williams*
his Attorney

Patented Mar. 15, 1927.

UNITED STATES PATENT OFFICE.

WILLIAM A. WILLIAMS, OF COLUMBUS, OHIO.

ELEVATOR-DOOR LATCH.

Application filed September 26, 1923. Serial No. 664,952.

This invention relates more particularly to elevators in which electricity is employed as the motive power and the object of the invention is to provide improved means for preventing the opening of the door until the car has arrived opposite the door or by persons outside the car and for preventing the starting of the car from such a position until the door is closed.

10 The invention is embodied in the example herein shown and described, the features of novelty being finally claimed.

In the accompanying drawing

Figure 1 illustrates in elevation the combined door latch and circuit closer, said parts being in the latched and circuit closing position.

Fig. 2 is a similar view showing the door latch disengaged and the circuit closer in the open position of the parts.

20 Fig. 3 is a vertical sectional view on a larger scale of the circuit closer in the closed position.

Fig. 4 is a similar view showing the circuit closer open.

Fig. 5 is a combined elevation and section showing the apparatus employed on the car for operating the circuit closer and door latch locking device.

30 The circuit closer shown in connection with the present invention is a modification of the device shown in my Letters Patent of the United States issued May 8, 1923, No. 1,454,095 and for a full description of that device reference is made to said Letters Patent. Briefly said device comprises a box 5 provided with contacts or electrodes 16 to which the wires 24 of the elevator operating circuit are connected and a cover 8 carrying

40 a circuit closer consisting of a strip of metal 13 adapted to be impinged upon the two electrodes 16 when the cover is closed by the operation of the upwardly pressed spring actuated door latch bolt 19. In the present invention the cover 8 is provided with a latch hook or stop 8^a pointing toward the door latch bolt the end of said hook when the cover is closed adapted to engage the notch 19^a in the upper end of the bolt to

50 prevent the withdrawal of the latch bolt when the cover is closed and locked as shown in Fig. 3. It is desirable that there be a slight capacity for lateral motion of the latch bolt in the plane of its closing movement when confined in latching position as shown in Figs. 1 and 3.

The cover 8 of the circuit closer box is provided with means for normally locking it in its closed position consisting of a bent finger 20 having affixed thereto a hinging pin 21 ⁶⁰ journaled along the upper corner of the box said bent finger 20 having a locking end 20^a adapted to reach under a base plate 22 at the under side of the cover when the latter is in closed position. The hinging pin 21 is ⁶⁵ equipped with a spring 23 adapted to press the said bent finger toward the said locking position. The hinging pin 21 is also provided with an arm 40 adjustably secured at one end thereto, said arm being provided ⁷⁰ with an antifriction roller 25 at its upper end.

The elevator or car is equipped with a shoe or cam 26 hinged by two links 27 to a bracket 28 secured to the car, said links permitting a lateral swinging movement of the cam into and out of a vertical path including the roller 25 and adapted by contact with said roller to remove the bent finger 20 from locking position. The character 29 designates an electro-magnet having a movable core or armature 30 normally held down by a coil spring 31 around a pin 32 connected with the lower end of the core and extending through a head 33 on the lower end of ⁸⁰ the electro-magnet 29. The upper end of the armature has connected with it a pin 34 and coupled to the latter is one end of a lever 35 fulcrumed on a bracket 36. The other end of the lever 35 is connected by ⁸⁵ means of a rod 37 with one arm of a bell crank lever 38 fulcrumed at 38^a the other end of said bell crank lever being connected to the cam or shoe 26 by link 39.

The electro-magnet referred to is included ⁹⁰ in the operating circuit 24 so as to be energized when the car is raised or lowered the door being closed. Hence when the car is being so raised or lowered the cam or shoe is out of line to operate the roller 25. When the current is broken, as when the controller is moved to stop the car, the cam or shoe is moved into position to actuate the arm 40 and hence release the latch of the cover 8, thus permitting breaking of the circuit at ¹⁰⁰ 105 the circuit closer box when the door is opened said breaking of the circuit being in addition to the breaking effected by the usual controller in the elevator car. The operating circuit cannot, therefore, be closed until the door is fully reclosed. Nor can the door be opened until the car is opposite it. ¹¹⁰

Because the operating circuit is effective on the electro-magnet when the car passes a floor the cam or shoe 26 is held out of position to operate the lock finger 20. The 5 operation of the circuit closer box is the same as in my former patent referred to except that in the present construction the latching bolt 19 is normally locked from withdrawal until the cover 8 is released by 10 the arrival and stopping of the car opposite the door.

It will be understood, of course, that the term power circuit includes any circuit used 15 in connection with the elevator—the car braking circuit for example.

The forms of the parts can be changed without departing from the gist of the invention as claimed.

What I claim is:

- 20 1. Apparatus for an electrically operated elevator including, in combination, a power circuit having electrodes included in the power circuit, a circuit closer case containing said electrodes and having a hinged 25 cover, a manually operated rectilinearly moving spring actuated door latch bolt carried by the car and adapted to engage said case when the door is closed, a circuit closer carried by the cover, said cover actuated by

the door latch bolt to close the circuit and hold the same closed, said cover also having a latch cooperating with the latch bolt to latch said bolt, means to latch the cover, means on the car controlled by the power circuit for releasing the last named latch 35 when the car arrives and is stopped at the door.

2. Apparatus for an electrically operated elevator including, in combination, a power circuit having electrodes included in the 40 power circuit, a circuit closer case containing said electrodes and having a hinged cover, a manually operated rectilinearly moving spring actuated door latch bolt carried by the cover, said cover actuatable by the 45 door latch bolt to close the circuit and hold the same closed, said cover also having a latch cooperating with the latch bolt to latch said bolt, means to latch the cover, means on the car and means consisting of a cam 50 and an electro-magnet actuated by the power circuit for releasing the last named latch when the car arrives and is stopped at the door, said electro-magnet also adapted to move said cam out of position to actuate said 55 last named latch.

WILLIAM A. WILLIAMS.
